MAGNETIC DOOR CATCH

Macy O. Teetor, New Orleans, La.

Application October 20, 1951, Serial No. 252,351

14 Claims. (Cl. 292—251.5)

1

This invention relates to a novel and improved magnetic door catch and more particularly to a magnetic catch adapted for use on cabinet doors of the blind panel type.

Among the more recent innovations in cabinet-ware and the like is the cabinet door of the blind panel type in which there is little or no visible hardware and which does not have the usual knob or handle for opening the door. Such doors require a special type of catch or latch mechanism which for convenience may be referred to as a "push-to-open" catch. When the door is moved to closed position, the catch operates automatically to secure the door in closed relation. When it is desired to open the door, the door is merely pushed inwardly to a slight extent and the so-called push-to-open catch is thereby automatically released whereupon the door is opened by the action of a spring or the like constituting part of the catch mechanism.

Several forms of push-to-open catches operating on strictly mechanical principles have been proposed heretofore and some have been made available commercially. However, such devices as a rule have been subject to the same disadvantages and defects inherent in all mechanical door catches which are dependent upon mechanical interengagement of cooperating catch elements mounted on the door and the door frame or other adjacent supporting structure. The most common difficulty in this respect arises from the very frequent misalignment of the co-acting catch elements due either to faulty initial installation or to sagging or warping of the various parts of the cabinet some time after the initial installation of the catch elements. As a result of misalignment, the door tends either to stick or jam in closed position or else the door is unable to close properly. In most cases the defect can be corrected satisfactorily only by completely removing one or both catch elements and remounting them in properly aligned positions.

As will hereinafter appear, my invention provides a door catch which embodies the push-to-open mode of operation but relies on magnetic attractive principles in order to overcome the aforementioned disadvantages of the strictly mechanical catches of this type.

Accordingly, a primary object of my invention is to provide a novel door catch of the character described which is not subject to misalignment difficulties and other defects of the mechanical devices heretofore suggested.

Another object of the invention is to provide

2

a novel door catch of the class described which incorporates magnetic operating principles.

A further object of the invention is to provide a novel magnetic door catch which is specially adapted for use with cabinet doors of the blind panel type which do not have the usual knob or handle for opening the door.

An additional object of the invention is to provide a novel magnetic door catch of the class described which comprises relatively few parts, which can be inexpensively manufactured, and which is capable of rapid and simple installation.

Other objects and advantages of the invention will become apparent from the subsequent detailed description of the invention taken in conjunction with the accompanying drawings, wherein:

Fig. 1 is a perspective view on a reduced scale of a fragmentary portion of a door and frame structure having a catch embodying the features of my invention;

Fig. 2 is an enlarged front elevational view of one unit of the catch as mounted on the frame;

Fig. 3 is a side elevational view of the catch unit as viewed from the right side in Fig. 2;

Fig. 4 is a vertical sectional view showing the portions of the catch elements when the door is in its normal closed position;

Fig. 5 is a rear elevational view as seen from the right in Fig. 4;

Fig. 6 is a view similar to Fig. 4 but showing the positions of the catch elements when the door is pressed inwardly to effect release of the catch and subsequent automatic opening of the door;

Fig. 7 is a transverse sectional view taken along the line 7—7 of Fig. 4;

Fig. 8 is a transverse sectional view taken along the line 8—8 of Fig. 4; and

Figs. 9 and 10 are fragmentary transverse sectional views showing the manner of assembly of the parts of the device.

Referring now to Fig. 1 of the drawings, a fragmentary portion of a door and frame structure is shown comprising a door 16 hingedly secured at one edge thereof to a frame having upright side portions 17 and a sill or base 18. The front edges, designated at 19, of the side portions 17 will be referred to as the finish face of the frame. The side members 17 are also provided with upright inwardly extending portions 21 which constitute the door jamb for limiting the inward movement of the door, as will hereinafter appear.

3

The door and frame structure is provided with a magnetic catch embodying the features of my invention and consisting of a swingable magnet unit 22 mounted at the inner face of the outermost door jamb 21 by means of a mounting device 23 and a cooperating armature unit comprising a plate 24 affixed in coacting position at the inner face of the door 16.

Referring now to Figs. 2 to 8 inclusive, the magnet unit 22 is shown as comprising an elongated housing or body member having oppositely disposed sides 26, a closed lower end portion 27, and a front wall 28 (Fig. 4) which curves upwardly from the closed end 27 and terminates at its upper end inwardly from the front edges of the side walls 26. The front wall 28 is provided with a rectangular aperture or opening 29 adjacent the lower end of the housing for receiving a magnet element, as hereinafter described. In addition, the upper portions of the side walls 26 are slanted or bevelled rearwardly, as at 31, to facilitate releasing movement of the magnet unit as will be described hereinafter in detail in connection with the operation of the device.

The magnet housing is pivotally or swingably mounted by means of a mounting plate 32 which is affixed to the inside face of the door jamb 21 by a plurality of screws 33 and is provided with an integral outwardly extending pivot pin or stud 34. The upper ends of the sides 26 of the magnet housing are formed with rearwardly-opening semi-circular apertures or half-bearings 36 which pivotally engage the stud 34 at the forward half thereof. Extending inwardly and upwardly from the sides 26 of the magnet housing are a pair of integral upright lugs or projections 37 (Fig. 2) providing forwardly-opening semi-circular apertures or half-bearings which fit around the stud 34 at the rear half thereof and axially intermediate the outermost half-bearings 36. The base of the supporting stud 34 is integrally formed with a boss or enlargement 38 which holds the magnet housing away from the heads of the screws 33 whereby to permit free and unobstructed swinging movement of the magnet unit on the stud 34. In addition, the central portion of the stud 34 is formed with an integral radially-projecting hump or protuberance 39 which is disposed intermediate the innermost half-bearings 37 for normally retaining the magnet unit on the stud 34. By reason of the discontinuous or semi-circular construction of the half-bearings 36 and 37, the swingable magnet unit can be readily assembled in operating relation on the stud 34, as will hereinafter be described.

The magnet housing may be conveniently fabricated as a die-casting and is preferably formed from a non-magnetic material such as brass, aluminum, or zinc. If desired, the magnet housing can also be formed from a suitable plastic.

Disposed within the hollow interior of the magnet housing is a permanent horseshoe magnet element magnet element 41 having a pair of spaced projecting pole pieces or legs 42 and a transverse connecting portion 43. Any suitable magnetic metal or alloy may be utilized for the magnet 41 but I prefer to use the alloy of aluminum, nickel, and cobalt known as "Alnico." The magnet 41 is disposed within the magnet housing with the legs 42 extending transversely in the direction of and projecting slightly through the opening 29 in the forward wall 28 of the housing. As will be clear from the drawings, the opening 29 through which the legs 42 of the magnet ele-

4

ment extend is slightly larger than the external dimensions of the magnet 41 so that there is sufficient clearance therebetween to permit limited angular or cocking movement of the magnet element relative to its housing. Extending between the sides 26 at the rear of the magnet housing is a cross member or backing plate 44 having a central bump or hump 46 against which the connecting portion 43 of the magnet seats to permit self-adjusting rockable movement of the magnet 41 in a generally horizontal plane.

An elongated resilient strap or spring 47, preferably having a round cross-sectional shape, is provided for retaining the magnet element 41 in assembled relation within the magnet housing and for coaction with the door 16 to effect automatic opening of the latter upon release of the catch mechanism. One end of the spring 47 is provided with a hook portion 48 (Fig. 4) which fits under the uppermost edge of the aperture 29 in the front wall 28 of the magnet housing, and the spring 47 curves upwardly over the stud 34 and thence downwardly and inwardly, as at 49, through the open rear portion of the magnet housing. The remaining portion of the spring 47 is substantially straight, as at 51, and passes downwardly between the legs 42 of the magnet and is retained at its extreme lower end 52 by engagement with the interior of the magnet housing adjacent the juncture of the lower end 27 and the front wall 28. By reason of the inherent resilience of the spring member 47, the straight portion 51 of the spring thereby presses against a rounded groove 53 which is integrally formed in the magnet element between the legs 42 thereof and the magnet is thereby resiliently held against the hump or protuberance 46 of the cross plate 44. As will hereinafter appear in connection with the description of the operation of the device, the spring member 47 has a normal outwardly bowed configuration adjacent the upper forward portion of the magnet unit and it is this portion of the spring 47 which coacts with the door 16 for opening the latter.

The armature unit of my device comprising the elongated flat plate 24 is formed from a magnetically permeable metal such as iron or steel and is secured to the inner face of the door 16 by means of a plurality of screws 54. It will be understood that the armature plate 24 is mounted in suitable coacting position on the door 16 to permit engagement of the magnet element 41 therewith when the door is in closed position adjacent the frame.

In Figs. 1, 2, and 3 the swingable magnet unit 22 of the catch is shown in its normal free-hanging position when the door 16 is open and the armature plate 24 is therefore outside of the region of magnetic attraction of the magnet element. As will be particularly evident from Fig. 3, the center of gravity of the magnet unit 22 is such that the unit normally hangs on a slight slant with the bottom end of the housing being disposed inwardly from the front face of the door jamb 21 and slightly to the rear of the pivot line defined by the stud 34.

When the door 16 is moved to its normal closed position, the magnetic attraction of the magnet element 41 for the armature plate 24 causes the entire magnet unit 22 to pivot forwardly about the stud 34 to a substantially vertical position (Figs. 4 and 5) with the contact faces of the magnet legs 42 engaging the corresponding flat surface of the armature plate 24. Thus, the swingable magnet unit 22 is now temporarily adhered

to or secured to the armature plate 24 and the outwardly bowed upper portion of the spring 47 engages the armature plate 24 in substantially tangential relation therewith and below the pivot line of the stud 34. With the magnet and armature thus in contact, the entire catch unit 22 serves in effect as a spacer for holding the door 16 in predetermined spaced relation from the door jamb 21. Although not shown in the drawings, it will be understood that the location of the stud 34 and the outwardly bowed conformation of the spring member 47 are so arranged that the outside surface of the door 16 will be held in substantially flush relation with the finish face 19 of the door frame when the door is in normal closed position, as illustrated in Figs. 4 and 5. In this position of the door, the spacing between the armature plate 24 and the coacting surface of the door jamb 21 may be relatively small, for example about $\frac{1}{8}$ or $\frac{1}{4}$ of an inch.

When it is desired to open the door, the door 16 is pushed inwardly, as seen in Fig. 6, until the armature plate 24 engages the door jamb 21. This movement obviously causes the magnet housing to rock inwardly about the stud 34 by reason of the camming engagement of the armature plate 24 with the forward edges of the sides 26 of the magnet housing. This inward rocking movement of the magnet housing is permitted by and facilitated by the slanted or bevelled shoulders 31 on the sides 26, as will be readily understood. Thus, when the magnet unit 22 is rocked to its rearwardmost Fig. 6 position, the armature plate 24 contacts the magnet housing substantially at the junctures of the slanted shoulders 31 with the lower straight portions of the housing sides 26, and the spring 47 is at the same time deflected or compressed rearwardly to the position shown in Fig. 6. The result of this camming action and inward rocking of the magnet unit is that the magnetic contact between the magnet element 41 and the armature plate 24 is disrupted thereby releasing the catch.

Following the limited inward movement of the door 16 to effect release of the catch mechanism as above described, the pressure on the door 16 is abruptly released whereupon the action of the spring 47 in engagement with the armature plate 24 below the pivot line of the stud 34 causes the door 16 to be pushed outwardly and away from the magnet unit before the magnet housing can swing forwardly to permit magnetic contact between the magnet element and the armature. In other words, the change in angularity of the magnet unit 22, as seen in Fig. 6, in conjunction with the increased spring pressure as a result of the displacement of the spring 47 provides a rapid and resilient opening movement of the door 16 so that the door is quickly pivoted beyond the effective region of the forces of magnetic attraction and before the magnet element 41 returns to its normal free-hanging position. Thus, it will be seen that the present device has the same general mode of operation as the strictly mechanical push-to-open catches heretofore known but the retention and release of the door is accomplished solely by establishing and disrupting magnetic contact between the magnet and armature elements of the device.

As hereinbefore pointed out, the chief disadvantage of the mechanical catches of the push-to-open type arises from the frequent misalignment of the catch elements due to misalignment of the door relative to the frame. Even when the most extreme care is exercised in the instal-

lation of a mechanical catch, it will usually be found in wood cabinetware that warping or sagging of the door and/or frame results in ultimate misalignment. This difficulty is obviated by my invention because the coacting catch elements are so arranged as to permit a substantial degree of self-adjustment and automatic alignment between the operating portions of the catch. Thus, it will be quite evident that because of the swingable mounting of the magnet housing on the stud 34, the magnet element 41 can readily accommodate itself in a generally vertical plane to compensate for any vertical misalignment of the door 16 whereby to permit full surface contact between the magnet legs 42 and the armature plate 24 even though the door may not be in parallel alignment relative to the frame. Similarly, the transverse rockable relation of the magnet element 41 with respect to the rear cross plate 44 of the magnet housing permits automatic self-alignment of the magnet element in a generally horizontal plane whereby to compensate for horizontal misalignment between the door and frame by permitting full surface contact between the magnet and the armature in a generally horizontal plane. The adjustability and self-alignment of the parts is further facilitated by the clearance provided between the periphery of the magnet element 41 and the housing aperture 29 so that the magnet element 41 can undergo limited angular or cocking movement relative to its housing. Thus, it will be understood that self-alignment of the parts is facilitated not only by pivotal or swinging movement of the magnet housing and magnet element as a unit but also by limited angular or cocking movement of the magnet element relative to its housing.

Although it will be understood that various means may be provided for pivotally mounting the magnet unit 22 on the door jamb 21, the specific structural embodiment comprising the plate 32 and the stud 34 illustrated herein is particularly desirable since it affords a minimum number of parts and may be readily fabricated by die-casting techniques. In Figs. 9 and 10 I have illustrated the manner of assembling the magnet unit 22 on the pivot stud 34. First, the magnet unit 22 is held in normal upright position with the legs 42 of the magnet element extending forwardly and the unit is then slid onto the stud 34 until the innermost half-bearing 37 engages the protuberance 39 on the stud, as seen in Fig. 9. Then, the magnet unit 22 is pivoted to inverted position with the magnet legs extending rearwardly whereby the innermost half-bearing 37 clears the protuberance 39. Thereafter, the magnet unit is moved axially and inwardly into abutment against the boss 38 at the base of the stud 34, as seen in Fig. 10, after which the unit is pivoted downwardly into normal operating position with the protuberance 39 extending between the half-bearings 37.

As a result of this simplified construction, it will be understood that the mounting plate 32 and its stud 34 can be installed on either side of the door jamb 21 and the swinging unit can be readily assembled in either the right-hand or left-hand position of the device. The installation of the device is further facilitated by the predetermined location of the stud 34 relative to the vertical side edges of the plate 32 so that the unit will be automatically disposed in proper operating position when the mounting plate 32 is installed with its forward edge in flush relation with the corresponding forward surface of

7
the door jamb 21. Thus, there is no need for precise measurements to insure accurate mounting of the swinging unit for proper operation.

Although the invention has been described herein in connection with a specific structural embodiment thereof, it will be understood that various equivalent structures and modifications may be resorted to without departing from the scope of the invention as defined in the appended claims.

I claim:

1. A magnetic door catch of the character described comprising armature means adapted to be mounted on a door, coating magnet means including a magnet support adapted to be movably mounted adjacent the door and a magnet element carried by said support and operatively engageable with said armature means for holding the door in normal closed relation in one position of said support, means on said support operatively engageable with the door for shifting said support to a different position in response to limited inward movement of the door from its normal closed position and thereby moving said magnet element away from the door and operatively disengaging said magnet element and said armature means, and spring means adapted for operative engagement with the door for opening the door following the disengagement of said magnet element and said armature means.

2. A magnetic door catch of the character described comprising armature means adapted to be mounted on a door, coating magnet means including a magnet support adapted to be pivotally mounted adjacent the door for swinging movement away from and toward the door and a magnet element carried by said support and operatively engageable with said armature means for holding the door in normal closed position when said support is in its forwardly pivoted position, cam means on said support operatively engageable with the door for swinging said support and the magnet element rearwardly and away from the door in response to limited inward movement of the door from its normal closed position thereby operatively disengaging said magnet element and said armature means, and spring means adapted for operative engagement with the door for normally urging the door outwardly whereby to effect opening of the door under spring pressure following the disengagement of said magnet element and said armature means.

3. A magnetic door catch of the character described comprising an armature element adapted to be mounted on a door, magnet housing structure adapted to be movably supported adjacent the door for movement away from and toward the door and having a magnet element mounted therein for coaction with said armature element, said magnet element being engageable with said armature element for holding the door in normal closed position when said housing structure is in its forward position and said housing structure having a portion operatively engageable with the door for moving said structure rearwardly in response to limited inward movement of the door from its normal closed position for disengaging said magnet element from said armature element, and spring means adapted for operative engagement with the door for normally urging the door outwardly whereby to open the door following the disengagement of said magnet and armature elements.

4. A magnetic catch of the character described for installation on a door and adjacent frame, comprising an armature element adapted to be mounted on the door, an elongated magnet housing adapted to be pivotally secured adjacent its upper end to the frame for swinging movement away from and toward the door, a magnet element supported adjacent the lower end of said housing and engageable with said armature element when said housing is in its forwardly pivoted position for holding the door in normal closed position, said housing having a cam portion operatively engageable with the door for swinging said housing rearwardly and away from the door and thereby disengaging said magnet and armature elements in response to limited inward movement of the door from its normal closed position into operative engagement with said cam portion, and spring means for opening the door following the disengagement of said magnet and armature elements.

5. A magnetic catch of the character described and adapted for installation on a door and adjacent frame, comprising an armature element rigidly mountable on the door, a swingable member pivotally securable on the frame for swinging movement away from and toward the door, a magnet element carried by the swingable member for coacting engagement with said armature element for holding the door in normal closed position when the swingable member is in its forwardly pivoted position, said swingable member having a cam surface adapted for operative engagement with the door and said magnet element being disengageable from the armature element to release the door in response to limited inward movement of the door from its normal closed position into operative camming engagement with said cam surface whereby to pivot the swingable member rearwardly, and spring means for automatically opening the door upon disengagement of said magnet and armature elements.

6. A magnetic door catch of the character described for installation on coating door and frame members, comprising an armature element adapted to be mounted on the door, magnet-supporting means adapted to be pivotally mounted on the frame adjacent said door for swinging movement in a vertical plane away from and toward the door, a magnet element rockably carried by said magnet-supporting means for limited angular movement in a generally horizontal plane and engageable with said armature element for holding the door in normal closed position when said magnet-supporting means is in its forwardly pivoted position, said magnet-supporting means having a portion operatively engageable with the door for swinging said magnet-supporting means rearwardly and away from the door and thereby disengaging said magnet and armature elements in response to limited inward movement of the door from its normal closed position into operative engagement with said portion, and spring means for opening the door following the disengagement of said magnet and armature elements, the swingability of said magnet-supporting means in a vertical plane and the rockability of said magnet element in a generally horizontal plane permitting flatwise full surface contact between said magnet and armature elements when said door and frame members are in misaligned positions.

7. A magnetic catch of the character described for installation on a door and adjacent frame, comprising an armature element adapted to be

mounted on the door, an elongated magnet housing adapted to be pivotally secured adjacent its upper end to the frame for swinging movement away from and toward the door in a vertical plane, a magnet element rockably supported adjacent the lower end of said housing for limited angular movement in a generally horizontal plane transversely of said housing and engageable with said armature element when said housing is in its forwardly pivoted position for holding the door in normal closed position, said housing having integral cam means adjacent its upper end operatively engageable with the door for swinging said housing rearwardly and thereby disengaging said magnet and armature elements in response to limited inward movement of the door from its normal closed position into operative engagement with said cam means, and spring means for opening the door following the disengagement of said magnet and armature elements, the vertical swingability of said housing and the generally horizontal rockability of said magnet element permitting self-alignment and flatwise full surface contact between said magnet and armature elements when said door and frame are in misaligned positions.

8. A magnetic catch of the character described for installation on coacting door and frame members, comprising an armature element adapted to be mounted on the door, magnet-supporting means adapted to be pivotally mounted on the frame adjacent said door for swinging movement away from and toward the door, a magnet element carried by said magnet-supporting means and engageable with said armature element in the forwardly pivoted position of said magnet-supporting means for holding the door in normal closed position, said magnet-supporting means having a portion operatively engageable with the door for swinging said magnet-supporting means rearwardly and away from the door and thereby disengaging said magnet and armature elements in response to limited inward movement of the door from its normal closed position into operative engagement with said portion, and spring means associated with said magnet-supporting means for retaining said magnet element in assembled relation therewith, said spring means having a portion adapted for operative engagement with the door for opening the latter under spring pressure following the disengagement of said magnet and armature elements.

9. A magnetic catch of the character described for installation on a door and adjacent frame, comprising an armature element adapted to be mounted on the door, an elongated magnet housing adapted to be pivotally secured adjacent its upper end to the frame for swinging movement away from and toward the door, a magnet element having a pair of spaced legs and disposed adjacent the lower end of said housing with said legs extending forwardly from the housing for engagement with said armature element when said housing is in its forwardly pivoted position for holding the door in normal closed position, said housing having shoulder means adjacent its upper end operatively engageable with the door for swinging said housing rearwardly and thereby disengaging said magnet and armature elements in response to limited inward movement of the door from its normal closed position into operative engagement with said shoulder means, and an elongated spring member having one end portion thereof extending

longitudinally within said housing and engaging said magnet element intermediate said legs for retaining the magnet element in assembled relation within said housing, the opposite end portion of said spring member extending upwardly and forwardly beyond said housing for operatively engaging the door and normally urging the latter outwardly whereby to effect automatic opening of the door upon disengagement of said magnet and armature elements.

10. A magnetic catch of the character described for installation on a door and adjacent frame, comprising an armature element adapted to be mounted on the door, an elongated magnet housing adapted to be pivotally secured adjacent its upper end to the frame for swinging movement away from and toward the door, said housing having a forward wall with an aperture therein adjacent the lower end of the housing, a magnet element disposed within said housing and having a pair of spaced legs extending forwardly through said aperture and engageable with said armature element when said housing is in its forwardly pivoted position for holding the door in normal closed position, said housing having shoulder means adjacent its upper end operatively engageable with the door for swinging said housing rearwardly and thereby disengaging said magnet and armature elements in response to limited inward movement of the door from its normal closed position into operative engagement with said shoulder means, and an elongated spring member retained at one end thereof within said housing and engaging said magnet element intermediate said legs for holding the magnet element in assembled relation within the housing, said spring member having a forwardly extending and outwardly bowed portion adjacent its opposite end adapted for operative engagement with the door and being compressible for increasing the spring pressure on the door during rearward swinging movement of said housing whereby to effect automatic opening of the door under the increased spring pressure following the disengagement of said magnet and armature elements.

11. A magnetic catch of the character described for installation on a door and adjacent frame, comprising an armature element adapted to be mounted on the door, an elongated magnet housing adapted to be pivotally secured adjacent its upper end to the frame for swinging movement away from and toward the door, said housing having a forward wall with an aperture therein adjacent the lower end of the housing and having a transverse supporting member spaced rearwardly from said aperture, a magnet element disposed within said housing in engagement with said supporting member and having a pair of spaced legs extending forwardly through said aperture for engagement with said armature element when said housing is in its forwardly pivoted position for holding the door in normal closed position, said housing having shoulder means adjacent its upper end operatively engageable with the door for swinging said housing rearwardly and thereby disengaging said armature and magnet elements in response to limited inward movement of the door from its normal closed position into operative engagement with said shoulder means, and an elongated spring member having one end portion extending longitudinally within said housing and engaging said magnet element intermediate said legs for retaining the magnet element in abutment against said supporting member

but permitting limited transverse rocking movement of said magnet element, said spring member extending forwardly from said housing at its opposite end portion for operative engagement with the door whereby to effect opening of the door upon disengagement of said magnet and armature elements.

12. A magnetic catch of the character described for installation on a door and adjacent frame, comprising an armature element adapted to be mounted on the door, an elongated magnet housing adapted to be pivotally secured adjacent its upper end to the frame for swinging movement away from and toward the door, said housing having a pair of oppositely disposed sides, a forward wall intermediate said sides and provided with an aperture adjacent the lower end of the housing, and a transverse supporting member spaced rearwardly from said aperture and having a central protuberance facing said aperture, a magnet element disposed within said housing and having a pair of spaced legs extending forwardly through said aperture for engagement with said armature element when said housing is in its forwardly pivoted position for holding the door in normal closed position, the sides of said housing being provided with rearwardly slanted upper end portions for facilitating rearward swinging movement of said housing with consequent disengagement of said magnet and armature elements in response to limited inward movement of the door from its normal closed position into operative camming engagement with said housing, and an elongated spring member having one end portion thereof extending longitudinally within said housing and engaging said magnet element intermediate the legs thereof for rockably retaining the magnet element against said protuberance, said spring member extending at its opposite end portion forwardly from said housing and thence curving downwardly into retained engagement at the upper edge of said aperture whereby to provide an outwardly bowed spring portion adapted for operative engagement with the door, said out-

wardly bowed spring portion being compressible during operative camming engagement of the door with said housing whereby to effect automatic opening of the door following the disengagement of said magnet and armature elements.

13. A magnetic door catch of the character described and adapted for installation on a door and adjacent frame, comprising an armature adapted to be rigidly mounted on the door, mounting means including an outwardly extending stud adapted to be rigidly affixed to the frame, an elongated swingable support pivotally secured on said stud for swinging movement away from and toward the door, a magnet element carried by said support and engageable with said armature element in the forwardly pivoted position of said support for holding the door in normal closed position, said support having integral cam means operatively engageable with the door for swinging said support rearwardly and away from the door and thereby disengaging said magnet and armature elements in response to limited inward movement of the door from its normal closed position into operative engagement with said cam means, and spring means for opening the door following the disengagement of said magnet and armature elements.

14. The device of claim 13 further characterized in that said swingable support is provided with a plurality of oppositely opening half-bearings pivotally engaged with said stud and said stud is provided with a central protuberance cooperating with said half-bearings for retaining the support against inadvertent axial movement upon said stud.
